CLAIM

I claim the ornamental design for a bottle, as shown and described.

DESCRIPTION

FIG. 1 is a front elevation view of a bottle showing my new design;

FIG. 2 is a right side elevation view thereof, the left side elevation view being identical;

FIG. 3 is a top, front perspective view thereof;

FIG. 4 is a top, right side perspective view thereof, the top, left side perspective being a mirror image; and,

FIG. 5 is a top plan view thereof.

The evenly dashed broken lines in the drawings illustrate the portions of the design that form no part of the claim. The dot-dash broken lines in the drawings define the bounds of the claim and form no part thereof.
